DESIGN FOR A CUSPIDOR STAND

Victor A. Noel, Brighton, and Arthur Hadley Murray, Rochester, N. Y., assignors to Ritter Company, Inc., New Castle County, Del., a corporation of Delaware

Application September 13, 1941, Serial No. 103,343

Term of patent 14 years

To all whom it may concern:

Be it known that we, Victor A. Noel and Arthur Hadley Murray, both citizens of the United States, residing at Brighton and Rochester, respectively, in the county of Monroe and State of New York, have invented a new, original, and ornamental Design for Cuspidor Stands, of which the following is a specification, reference being had to the accompanying drawing, forming part thereof.

Fig. 1 is a side elevational view of a cuspidor stand, showing our new design;

Fig. 2 is a front elevational view of the same.

We claim:

The ornamental design for a cuspidor stand, substantially as shown.

VICTOR A. NOEL.
ARTHUR HADLEY MURRAY.
